ELECTRIC MULTIPLE INDICATOR PANEL FOR A PNEUMATIC TUBE SYSTEM

Herbert Kalendar, Miami, Fla., assignor to Advance
Metal Products, Inc., Miami, Fla.

Filed Sept. 10, 1970, Ser. No. 24,908

Term of patent 14 years

Int. Cl. D13—03

U.S. Cl. D26—13

The figure is a perspective view of an electric multiple indicator panel for a pneumatic tube system, showing my new design.

The rear side thereof is plain.

I claim:

The ornamental design for an electric multiple indicator panel for a pneumatic tube system, as shown and described.
